UNITED STATES PATENT OFFICE

WILLIAM F. GROENE, OF CINCINNATI, OHIO, ASSIGNOR TO THE R. K. LE BLOND
MACHINE TOOL COMPANY, OF CINCINNATI, OHIO, A CORPORATION OF OHIO

FEED-CHANGE MECHANISM FOR LATHES

Application filed May 18, 1931. Serial No. 538,160.

My invention relates to lathes, and especially to the mechanisms transmitting power to the devices which feed the tool to the work, usually supported by the lathe carriage, and principally located in the apron of the carriage.

An object of my invention is to incorporate mechanism of such character in a compact assembly, with comparatively simple and inexpensive construction, suited to small lathes of good quality but sold at a comparatively low price.

Other objects will appear in the course of the following description, illustrated by the accompanying drawings, in which—

Figure 1 is a general perspective view of an engine lathe of a type in which my improvement is most advantageously used as above explained, showing the carriage and its cross feed and apron with said improvement embodied therein.

Figure 2 is a front elevation of the carriage and its apron, embodying my improvements, interiorly located parts of which are generally indicated by dotted lines, and also showing adjacent parts of the bed, rack, lead screw and feed rod, and showing the cross-feed screw but omitting the handle thereof as well as the cross slide.

Figure 3 is a partial horizontal cross section on the plane of the line 3—3 of Figure 2.

Figure 4 is a similar section on the plane of the line 4—4 of Figure 2.

Figure 5 is a partial vertical front-to-rear section on the plane of the line 5—5 of Figures 2 and 6.

Figure 6 is a partial rear elevation of the apron, showing part of the top of the carriage in vertical cross section on the plane 40 of the line 6—6 of Figure 5, but omitting the rack and bed.

The bed 1 of a lathe has the usual ways or V's 2 for guiding the carriage 3. Mounted on the left end of the bed is the usual head stock 4 understood as equipped with usual quick change gears and motor drive; and on the right hand end is the usual tail stock 5. Mounted on the front of the bed and extending through the apron 8, depending from the front of the carriage 3, is the usual lead screw

6 and the feed rod 7, driven in the usual manner from the gearing in the head stock 4.

Mounted on a rearwardly extending stud in the apron 8, is a bevel gear 9, this gear having a unitary rearwardly extending concentric wide faced spur gear 10. A pull pin 11 is mounted from front to rear in a bearing 12, and has on its inward end a spur gear 13, and a second concentric small spur gear or pinion 14, these gears having a running fit on a reduced portion of the pull pin 11, and being held thereon by a nut 15, the gear 13 being in mesh with wide faced gear 10. The pull pin 11 is capable of adjustment to three positions being held in each by a spring detent plunger 16 (Fig. 4) seating itself in any one of three detent notches 17 in the pull pin 11, being thus adapted to hold the gears 13 and 14 in a rear position or a front position, or in a middle neutral position.

Journaled in the apron 8, is a stud shaft 18, on a front to rear axis. Fixed on this stud shaft are a spur gear 19 and a smaller rear spur gear 20; this smaller gear meshes with the rack 21 secured to the underside of the V's 2 on the bed 1. Meshing with the gear 19 is a smaller spur gear 22 fixed on a shaft 23 in the bearing 23 in apron 8; the outer end of the shaft 23 having secured to it a hand wheel 24. With the pull pin 16 holding the gears 13 and 14 in the middle or neutral position, the carriage 3 and apron 8 can be manually traversed along the bed in either direction, by the turning of hand wheel 24, through gears 22, 19 and 20 and coaction of the latter with the rack 21.

Mounted to rock on a stud 25 fixed in the apron 8, is a lever 26, having a handle 27 for manual operation and a spring detent pin 28 for holding it in selected positions, the end of the detent pin entering locating depressions 29. There is also provided a pair of stop pins 29a for limiting the arc of movement sidewise.

Fixed in this lever 26 is a shift pin 30 extending in through a slot 30a in the apron 8 and carrying on its rear end a shifter shoe 31 which engages in a slot 32 in the hub 33 of the bevel pinion 34. When the lever 26 is shifted to the left the bevel pinion 34 is

carried to the left by the shifter pin 30 and meshes with the bevel gear 9.

The bevel pinion 34 has a key 35 which engages the keyway 35' in the feed rod 7, and is 5 driven by this rod, receiving its power from the usual change gear box at the head of the lathe.

If now it be desired to traverse the carriage, the pull pin 11 is moved inward 10 to its innermost or rear position of detent, thus bringing gear 14 into mesh with gear 19 and thus with the rack 21 by the rack gear 20, so that axial feed is derived from the feed rod 7.

15 If, however, it be desired to feed the cross slide (not shown) on the carriage, then the pull pin is pulled to its outward or front position of detent until the gear 13 is in mesh with gear 36 which is fast on the cross feed screw 36' which is then driven by the gear from the feed rod 7.

It is thus seen that it is impossible for the operator to throw the carriage feed and the cross slide feed in at the same time, avoiding 25 spoiling of work as sometimes occurs without this safeguard. The bevel gear 34 has its hub 33 rotatably mounted in the bearing block 37 fixed on the rear face of the apron 8, with its front open to admit and allow the 30 horizontal movement of the shifter pin 30. In the top of this block 37 is a half round transverse groove 37' in which the lead screw 6 bears. The half nut 38 for engagement with the lead screw 6 when chasing a thread 35 is movable up and down in a dovetail slot 39 in the rear side of the apron 8. The bearing block 37 is fixed in the lower part of the slot 39 by pins 39', as shown in Figure 6.

Secured in apron 8 is a stud 40 on which 40 swings a lever 41 controlled as to its positions by a friction bushing 42 around the stud 40. Projecting rearwardly from the lever 41 is a pin 43 passing back through a slot 44 in the wall of apron 8 and entering a horizontal 45 straight slot 45 opening forwardly in the front wall of the half nut 46. This straight slot 45 forms a cam surface for the pin 43 moving along an arc when the lever 41 is moved upward or downward. When moved 50 downward the lever meshes the half nut 38 with the lead screw 6, and when moved upward it lifts the half nut 38 free of the lead screw.

Secured to the lower portion of the half 55 nut 38 in a slot 46 in the top of the bearing block 37 is a pin 47. This pin 47 when the half nut 46 is at its lowest point and in engagement with the lead screw 6 is in the path of movement of the shift pin 30 and serves 60 as a lock preventing meshing of the bevel gear 34 with the bevel gear 9, and thus preventing driving of the cross feed from the feed rod 7.

65 This arrangement prevents any possibility of the operator throwing in the longitudinal

and cross feeds during the engagement of the half nut with the lead screw for cutting a thread, and, vice-versa, when the longitudinal feed is in, the half nut cannot be lowered to engage the lead screw, since the pin 47 will strike the shift pin 30 and prevent the half nut moving downward far enough to engage the lead screw threads.

The top seat or groove 37' in the bearing block 37 prevents any distortion and excessive wear of the lead screw 6 by the engagement of the half nut 38 therewith, thereby maintaining the accuracy of the lead screw 6 for cutting threads.

With the construction above described, if 80 for instance a thread is to be cut, the half nut 38 is lowered by raising the lever 41 to mesh with the lead screw 6. It will be possible to lower the half nut 38 only if the shift pin 30 is at the right end of its travel allowing the 85 pin 47 on the half nut to pass down beside the pin 30 as seen in Figure 3 with the bevel gear 34 out of mesh with the bevel gear 9 as seen in Figure 4 so that the train of gears which would connect the feed rod 7 with the 90 cross feed or rack feed is disconnected from the feed rod and the cross feed may be set by hand to cut the thread in the usual manner.

Or suppose that a longitudinal power feed 95 is desired for plain turning, the half nut 38 must be raised by depressing the lever 41 to withdraw the pin 47 out of the path of the pin 30 to permit meshing of the bevel gears 34 and 9; and the spur gears 13 and 14 will 100 be slid inward with the plunger 16 in the innermost notch 17 so that the smaller one 14 of these gears will mesh with the larger gear 19 of the third unit; the smaller gear 20 of this unit being constantly in mesh with the 105 rack 21. Thus the feed rod can drive the carriage axially of the work; and since for this meshing of the gears 14 and 19, the gear 13 cannot be in mesh with the gear 36 of the cross feed, there is no possibility of the operator running the cross feed in or out by power inadvertently during such plain turning. Such setting of the cross feed of course 110 remains possible manually by use of the cross feed handles where different diameters of 115 plain turning are to be made.

Supposing that the work is to be faced by feeding the tool at an angle to the axis of the work, the setting of the half nut 38 and the thus permitted meshing of the gears 34 and 120 39 are the same as just described but the slide gear unit is slid outward with the plunger 16 in the outermost notch 17 meshing the larger gear 13 of this unit with the cross feed gear 36; and as this meshing makes impossible the meshing of the smaller gear 14 of this unit with the larger gear 19 of the unit coaxing with the rack 21, there can be no axial movement of the carriage and the cross feed thereon by power due to inadvert- 125 130

ence of the operator. However, since the pinion 22 of the hand wheel 24 meshes with the gear 19 of the rack feeding unit, axial movement of the carriage may be made manually by turning the hand wheel 24 for fac-

ing in different planes.

Supporting that the operator desires to manually operate both the rack feed and the cross feed, the gears 13 and 14 may be placed 10 in neutral position as shown in the drawings relieving the operator of the duty of turning these gears 13 and 14 and the wide spur gear 10 and bevel gear 9. It will be seen that the operator may work in this way with the 15 gears 13 and 14 neutral even if the bevel gears 9 and 34 are meshed which would practically lock against the manual operation of the rack feed and cross feed were either slide gear 13 or 14 in mesh with the rack feed gear 19 20 or the cross feed gear 36 respectively because the operator would be attempting to turn the feed rod 7 which of course is connected to the train of driving gears at the head of the lathe and is very hard to turn in this 25 manner.

Notwithstanding the variety of relations which may be thus created between the various operating elements of the lathe and the carriage, the entire mechanism all is contained 30 within and upon an apron of very limited dimensions, appropriate for a small inexpensive lathe; and because the hand wheel 24, the knob of the pull pin 11, the handle 27 of the lever 26 and the handle of the lever 41, 35 are all close together on this relatively small compact apron, the manipulation of the lathe is rendered very convenient. Also as the result of the compact arrangement, the necessary movement of any of the parts is very 40 small which also adds to the convenience of manipulation as well as permits the various parts to be of comparatively heavy and sturdy construction and permitting a high 45 degree of accuracy for such an inexpensive lathe. The use of the half nut 38 with threads, while leaving the depression 37 in the bearing block 37 threadless, also permits of desirable accuracy in the lead screw connection without undue expense since the necessity of accurately aligning the threads of 50 two different members both accurately to fit the lead screw 6 is avoided; and the unthreaded depression 37' affords a sufficient support for the lead screw with relation to 55 the nut 38 with ample bearing between it and the tops of the lead screw threads as durable as the rest of the bearing parts of the apron construction.

I have illustrated and described my invention somewhat specifically but it will be understood that various modifications may occur within the scope of my invention and that I am not limited to such precise disclosure but what I claim as new and desire to secure 65 by Letters Patent, is:

1. In a lathe in which there is a carriage and an apron depending from the carriage and mechanism in back of said apron comprising a feed screw, a feed rod below the feed screw and a set of tool-feeding gears supported in said apron on front-to-rear axes, including a bevel gear, and a bevel pinion splined on the feed rod to shift into or out of mesh with said bevel gear and having an extended hub, said apron having a vertical slot in its back with undercut sides, a bearing block fixed in said slot and fitting said sides thereof and embracing said pinion hub and having a half bearing in its top supporting said feed screw, a half nut slidably fitting in said slot to shift up and down out of and into mesh with said feed screw, and devices movable on front-to-rear axes in said apron, one device comprising means for shifting said half nut and the other device comprising means for shifting said pinion.

2. A lathe as set forth in claim 1, in which the half nut has a transverse slot in its front and the device for shifting said half nut comprises a projection engaging in said transverse slot.

3. A lathe as set forth in claim 1, in which the pinion hub has an annular groove there-around within the bearing block, and the bearing block has an opening in its front, and the device for shifting the pinion comprises means extending back through said opening and engaging in said hub groove.

4. A lathe as set forth in claim 1, in which the pinion hub has an annular groove there-around within the bearing block, and the bearing block has an opening in its front and an opening in its top extending into its front opening, and the device for shifting the pinion comprises a projection extending back through said front opening and engaging in said hub groove, and the half nut has a projection extending down through said top opening to enter the path of the pinion-shifting projection when said half nut is meshed with said feed screw.

5. A lathe comprising a carriage and an apron having a slot with undercut sides, tool-feeding gears on front-to-rear axes on said apron, a feed rod to drive said gears, a feed screw to feed said carriage, and a bearing for the feed rod and feed screw, slid into said slot and fixed on said apron.

6. In a lathe in which there is a carriage and an apron depending from the carriage and feeding mechanism in back of said apron comprising a feed rod, and a pinion splined on the feed rod to shift into or out of mesh with part of said mechanism, a bearing block on the back of said apron, embracing and allowing sliding of said pinion, said apron and said bearing having an aperture opening through the front of said apron, and operating means on the front of said apron, extending back through said aperture and opera-

tively engaging said pinion within said bearing block, to shift said pinion.

7. In a lathe in which there is a carriage and an apron depending from the carriage and feeding mechanism in back of said apron comprising a feed screw, a feed rod, and a pinion splined on the feed rod to shift into or out of mesh with part of said mechanism, a bearing block on the back of said apron, embracing and allowing sliding of the pinion, said apron and said bearing having an aperture opening through the front of the apron, and said bearing block having an aperture opening from its front aperture to
